Assistant Examiner—Carol Rademaker
Attorney, Agent, or Firm—Michael V. Drew[57] **CLAIM**

The ornamental design for a carton, as shown and described.

DESCRIPTION

FIG. 1 is a perspective view of a carton showing my new design;

FIG. 2 is a top plan view thereof, the bottom plan view being identical;

FIG. 3 is a side elevation view thereof the opposite side being a mirror image;

FIG. 4 is another side elevation view thereof, the opposite side being a mirror image; and,

FIG. 5 is a plan view of the carton of FIG. 1 in unfolded condition.

The broken lines shown in FIG. 5 represent fold lines.
